UNITED STATES PATENT OFFICE

GEORGE BODEN, OF WATERBURY, CONNECTICUT, ASSIGNOR TO SCOVILL MANUFACTURING COMPANY, OF WATERBURY, CONNECTICUT, A CORPORATION OF CONNECTICUT

WINDOW-SCREEN CLIP

Application filed February 14, 1929. Serial No. 339,769.

This invention relates to window screens and more particularly to screens of the expansion or adjustable type.

In expansion screens one frame section 5 overlaps another and the two sections are relatively movable to make the effective screen area larger or smaller.

In order to obviate the necessity of sliding contact throughout the length of the overlapped portion, it has been proposed to associate individual bearing elements of relatively small area between the two frame sections. Such elements, however, as heretofore known, have been subject to various 15 objections. For example, they do not give proper sliding contact; they are expensive to manufacture and difficult to assemble; and they are liable to work loose under use.

It is an object of the present invention to 20 provide an expansion screen having individual bearing elements, such that these elements are economical to manufacture and assemble; such that they are firmly held in place; and such that the screen sections have 25 easily sliding action without sticking.

It is a further object of the invention to construct the bearing element of sheet metal, thereby producing a simple, cheap, yet effective construction and one which is 30 adapted for manufacture in large quantities at low cost.

Another object is to provide a firm and uniform anchorage for the bearing element.

With these general objects in view the invention consists in the features, combinations, details of construction and arrangements of parts which will first be described in connection with the accompanying drawing and then more particularly pointed out.

40 In the drawing:

Figure 1 is a perspective view, with parts broken away and in section, of an expansion screen constructed in accordance with the invention;

45 Figure 2 is a sectional view (enlarged) taken on the line 2—2 of Fig. 1; and

Figure 3 is a perspective view of a bearing element removed and enlarged.

50 Referring to the drawing, the screen illustrated as an example comprises two wooden

frame sections. One section, which may be termed the inner section, comprises a top bar or moulding 5 and a bottom bar 6 connected at one end by an end strip 7. The other section, which may be termed the outer section, comprises corresponding top, bottom and end pieces 5^a, 6^a, and 7^a. At the overlapping ends the frames are open.

Suitably secured in the frame sections are screens proper 8, 9 of wire mesh or other suitable material. At the open ends of the frame the screens have finishing strips 10, 11. Extreme open position of the screen is fixed by the mutual engagement of these 55 finishing strips. Extreme closed position is fixed by the engagement of the top and bottom bars of one frame section with the end strip being thicker than the other strips to provide stop shoulders.

In the construction illustrated, the two frame sections have complementary grooves for receiving individual bearing elements. The inner section has one or more bearing elements sliding in the groove of the outer section, and outer section has one or more bearing elements sliding in the groove of the 60 inner section.

In the exemplification here illustrated, the top bar 5 has a dovetail groove 12, undercut upwardly and downwardly as appears in Fig. 2. The top bar 5^a has a similar but reversely faced groove 12^a. Anchored in the open end of groove 12 is a bearing element, hereinafter described, having a portion arranged to slide in groove 12^a. A similar bearing element is anchored in the open end of groove 12^a to slide in groove 12.

These grooves and bearing elements are duplicated in the bottom bars of the respective frame sections. Thus, all the direct 65 sliding contact is taken by the four bearing elements, whereby sliding friction is reduced to a minimum.

The invention in its entirety includes a bearing element of metal having anchoring teeth which are arranged to anchor the element in the groove at both sides thereof. In the embodiment here shown as an example, the bearing element is a clip 15 having a 70 smooth side 16 and depending sides 17

100

which are concaved so as to be accommodated in the opposed dovetail grooves, as in Figure 2. The clip is substantially U-shaped in transverse cross-section. The depending sides terminate in prongs or teeth which are preferably four in number, two for each side. Each tooth is formed, for example, by slitting the metal obliquely as at 18 and providing a limiting aperture 19 at 10 the end of the slit and then by bending out the metal at the acute angle into a plane offset from that of the side into the teeth 20.

When the clip is assembled, the smooth side 16 coacts with the bottom of its groove, 15 the teeth anchor the clip in the opposed groove, with two teeth biting into the material at each side, and the concaved connecting sides cooperate with the dovetail sides of the grooves to hold the two sections 20 together while allowing sliding movement of the sections. Thus, the clip serves as a bearing member and also serves to hold the two sections together. There is a smooth easy running contact for the section that 25 rides on the clip as a bearing, as there is no cut metallic edge offering resistance. On the contrary, bent edges between the flat side 16 and the depending sides 17 are smooth and offer little friction opposing 30 movement.

To assemble the parts, the four clips 15 are inserted by hand as far into the open ends of the grooves as possible. The sides, 16, of the clips are slid into the respective 35 grooves and the dove-tailed connections prevent wabbling of the clips in the grooves. Then the screen sections are given a sharp, firm closing movement. This closing forces the clips into final position in the grooves, 40 the teeth biting into the relatively soft wood, thereby anchoring the clips in place. The toothed sides enter their grooves without difficulty, as the clips are held in proper longitudinal alignment by virtue of the dove-tailed connections with the other section. The teeth are in the nature of prongs which extend in angular fashion from the 45 sides of the clips. The prongs bite into the material of the sides of the grooves and 50 provide a firm, uniform anchorage for the clip in the groove,—an anchorage which extends uniformly over the entire anchored portion of the clip. In the clip shown, the teeth provide four, uniformly spaced points 55 of anchorage and a rigid assembly of the clip in the groove.

The construction described gives an easy sliding movement without tendency to stick; the clips are economical to manufacture as they can be produced from sheet metal by a simple stamping and bending operation; and the clips are easily assembled and firmly anchored without the necessity of tools or extraneous fastenings.

65 While the invention is capable of various

embodiments, it is noted that the clips here illustrated are adapted to use with a more or less common form of groove.

What I claim is:

1. In a window screen, and in combination, complementary frame sections, means for sliding said frame sections one upon the other comprising grooves cut in the front sections, and metallic bearing members for the grooves, said members being formed of sheet metal of substantially U-shaped transverse cross-section, the bight portions of said members being smooth and the ends of the leg portions being toothed. 70

2. In a window screen, and in combination, complementary frame sections, means for sliding said frame sections one upon the other comprising dovetail grooves arranged in opposed relation in adjacent frame sections, and metallic bearing members for the grooves, said members being formed of sheet metal of substantially U-shaped cross-section, the bight portions of said members being flat and smooth to allow one section to slide thereon, the leg portions being concaved for interlocking the dovetail grooves and having teeth struck out of the metal for biting into the sides of the grooves of the section. 80

3. A bearing element for relatively sliding members comprising a unitary piece of sheet metal with a substantially U-shaped transverse section and having a flat, smooth bight portion for engaging a groove in one member and leg portions with teeth struck out of the metal for biting into the sides of a groove in the other member. 95

4. A bearing element for relatively sliding members comprising a unitary piece of sheet metal with a substantially U-shaped transverse section and having a flat, smooth bight portion for engaging a groove in one member and leg portions with teeth struck out of the metal for biting into both sides of a groove in the other member, the leg portions being concaved to provide a dove-tailed running portion. 105

5. A bearing element for relatively sliding members comprising a unitary piece of sheet metal with a substantially U-shaped transverse section and having a flat, smooth bight portion for engaging a groove in one member and leg portions with teeth projecting therefrom, said teeth being formed by oblique slits in the metal terminating in limiting apertures, the metal at the acute angles being bent out from the planes of the leg portions. 115

6. A metallic bearing element for relatively sliding sections comprising a portion for sliding relative movement in a groove in one section, said portion being smooth throughout its contact with the walls of the groove and without any cut edge contacting with the material of the walls, and means 125

for anchoring said element to the other section.

7. A metallic bearing element for relatively sliding sections, comprising a unitary piece of sheet metal having a bight portion and leg portions extending therefrom, the bight portion being adapted for sliding movement in a groove in one section, and means for anchoring the leg portions to the other section.

8. A metallic bearing element for relatively sliding sections, comprising a unitary piece of sheet metal having a smooth flat side for running in a groove in one section and leg portions extending obliquely from said side and integrally united therewith, the connections between said side and portions being smooth bends in the metal, the leg portions being concaved to provide dovetail running portions and having teeth struck-out from the metal for anchoring the leg portions to the other section.

In testimony whereof, I have hereunto set my hand.

GEORGE BODEN.
